UNITED STATES PATENT OFFICE.

SAMUEL J. DUNKLEY, OF KALAMAZOO, MICHIGAN, ASSIGNOR TO THE DUNKLEY COMPANY,
OF KALAMAZOO, MICHIGAN, A CORPORATION OF ILLINOIS.

PEACH SPLITTING AND PITTING MACHINE.

No. 921,523.

Specification of Letters Patent.

Patented May 11, 1909.

Application filed February 27, 1905. Serial No. 247,467.

To all whom it may concern.

Be it known that I, SAMUEL J. DUNKLEY, a citizen of the United States, residing in Kalamazoo, in the county of Kalamazoo and State of Michigan, have invented a new and useful Improvement in Peach Splitting and Pitting Machines, of which the following is a specification:

My invention relates to improvements in peach splitting and pitting machines.

The object of my invention is to provide a peach splitting and pitting machine of a simple, efficient and durable construction, by means of which peaches may be rapidly and cheaply split or halved, and pitted or stoned, and the split halves of the peach separated from the stone without waste, mutilation or injury to the appearance of the fruit.

My invention consists in the means I employ to practically accomplish this object, or result; that is to say it consists, in connection with an intermittently rotating knife carrier or wheel having a series of knives mounted peripherally thereon, and each having a recessed cutting edge, preferably of a U-shape or V-shape, of a pair of movable forks reciprocating transversely to the plane of the knife carrier or wheel, and an opposing movable double or split knife co-operating in turn with each of the knives on the knife carrier or wheel, the two members of the split or double knife being adapted to separate or spread apart and thus separate the two split halves of the peach from the pit while the pit is grasped and held by the forks. My invention also consists in the novel construction of parts and devices and in the novel combinations of parts and devices herein shown or described.

In the accompanying drawing, forming a part of this specification, Figure 1 is a plan view of a peach splitting and pitting machine embodying my invention; Fig. 2 is a front elevation; Fig. 3 is a detail section on line 3—3 of Fig. 2; Fig. 4 is a detail vertical section on line 4—4 of Fig. 2, and Fig. 5 is a detail section on line 5—5 of Fig. 2; Figs. 6 and 7 are enlarged detail vertical sectional views illustrating the operation.

In the drawing A represents the frame of the machine, B is the intermittently revolving knife carrier or wheel, having a series of

knives C removably secured thereto. Each of the knives C has a recessed cutting edge c, the same being curved or U-shaped, and affording a hollow or cavity c¹, large enough to accommodate the peach pits, in connection with a similar cavity in the opposing or co-operating split knife D, which has a recessed cutting edge d likewise, of U-shape, and forming a cavity d¹ to receive the stone or pit x of the peach X. The knives C are secured to the carrier B by screws c². The cavity d¹ in the split or double knife D is preferably deeper than that in the knives C, so that the edges of the two knives D C may telescope or pass each other without striking the peach pit.

The split or double knife D is preferably composed of two thin steel knife blades D¹ D¹ having shanks of spring material the two members of the split knife fitting astride of the knife C on the carrier B when the split or double knife is closed down upon the peach to split the same. The two knife blades D¹ D¹ of the split or double knife D, are adapted to separate or spread apart after the peach is severed by the operation of the knives D, D, and thus cause the two split halves X¹ X¹ of the peach to be freed or separated from the pit x while the latter is held by the forks F F. The double or split knife D is given a vibrating movement to open and close against the co-operating knife C on the carrier B, and each spring knife blade D¹ is preferably removably secured by screws d² to a vibrating lever D², which is or may be of yoke-form, and pivoted to the frame at d³. The two spring knife blades D¹ D¹ are separated or spread apart after the same make their downward stroke to sever the peach, by means of a rotating cam G, which is furnished with a cam face g on each side, and which is preferably mounted to rotate between the two knife blades D¹ D¹.

The transversely reciprocating pit holders or forks F F are each preferably furnished with three tines f, and the same reciprocating through a pair of stationary stripper plates H H, which serve to strip the two split halves X¹ X¹ of the peach from the forks.

To facilitate the sticking or insertion of the peaches on the knives C of the carrier wheel B, a stationary hopper or peach guide H¹ is provided.

K is the discharge chute into which the split halves of the peaches and the pits drop after being operated upon by the machine, and M is a conveyer trough or endless conveyor for conveying the peaches to the inspecting or filling table, the pits dropping through the slots of the chute K, which is or may be formed of slats.

The knife carrier or wheel B has a step by 10 step or intermittent movement. The forks F F have a plain reciprocating movement, properly timed to pierce the peach and grasp the pits and hold the same while the two split members D¹ D¹ of the double or split knife 15 D spread apart or separate from each other to free the two halves of the peach from the pit, after said split or double knife D descends and severs the peach by its coöperation with the knife C. The split or double knife D has 20 two movements, one a vibrating or descending movement to sever the peach, and then a spreading or separating movement of its two blades D¹ D¹.

The required movements may be communicated 25 to the several moving parts of the machine by any suitable connecting or motion giving mechanism or gearing. The knife carrier or wheel B is intermittently rotated as required by an ordinary Geneva 30 stop mechanism, the same as illustrated in the drawing, comprising a radially slotted disk b connected to rotate with the wheel B, and a continuously rotating disk b¹, having a pin b² engaging the radial slots b³ of the disk 35 b. The disk b¹ is continuously rotated from the driving shaft P through the gears p on the driving shaft, and the gear p¹ on the shaft of the disk b¹. The knife holder or lever D² is pivoted to the frame at d³, and is vibrated or 40 operated at intervals as required by means of a cam P¹ on the driving shaft P, through the connecting lever d⁴, pivoted to the link d⁵. The lever d⁴ has an anti-friction roller d⁶ engaging the cam P¹. A spring d⁷ serves to 45 hold this roller d⁶ in engagement with the cam, and thus operates to retract the knife carrying lever. The cam G by which the two spring knife blades D¹ D¹ of the split or double knife D, are spread apart or separated 50 at intervals as required, may preferably be rotated by means of a sprocket wheel or gear g⁴ on its shaft g¹, and a sprocket chain g², which engages a sprocket wheel or gear g³ on the shaft b³. 55 Each of the reciprocating pit holders or forks F is reciprocated as required by means of a cam P² on the driving shaft P through the connecting lever f¹, having a roller f² engaging said cam P², and a connecting link f³, 60 bent lever f⁴, and pivot link f⁵. A spring f⁶ serves to hold the lever f¹ in engagement with the cam, and thus to retract the pit holder or fork F. The pit holders or forks F reciprocate in suitable guides F² on the frame of the 65 machine.

In operation, the attendant places or sticks the peaches, one by one, on the knife C as the knife carrier B rotates intermittently. At each step of the knife carrier or wheel B the opposing split or double knife 70 D descends and severs the peach, the cavities c¹ d¹ of the knives C, D accommodating the pit. The two members or blades D¹ D¹ of the split or double knife D are then caused to spread or spring apart by action of the 75 cam G, thus freeing the two split halves of the peach from the pit, which is still grasped or held stationary by the forks or pit holders F F. The forks F F next recede, thus stripping the halves of the peach from the 80 forks through the action of the stationary strippers H H, while at the same time the knife D moves upward and the carrier B moves another step, thus bringing another peach into position for operation. 85

I claim:

1. In a peach splitting and pitting machine, the combination with an intermittently rotatable knife carrier or wheel, furnished with a series of knives having recessed cutting edges mounted thereon, of a coöperating split or double knife mounted and operating in the plane of said wheel, a pair of movable pit holders or forks reciprocating transversely between said knives, and means for separating the two members or blades of said split or double knife and moving them with the split halves of the peach away from the said knife carrier, and thus freeing the split halves of the peach from the pit, substantially as specified. 90

2. In a peach splitting and pitting machine, the combination with an intermittently rotatable knife carrier or wheel furnished with a series of knives having recessed cutting edges, of a pair of transversely reciprocating pit holders or forks, a coöperating split or double knife mounted and operating in the plane of said wheel and comprising two flat blades of spring material, a yoke connecting said blades, and means for separating the two members or blades of said split or double knife and moving them away from the knife carrier, substantially as specified. 105

3. In a peach splitting and pitting machine, the combination with an intermittently rotatable knife carrier or wheel furnished with a series of knives having recessed cutting edges, of a pair of transversely reciprocating pit holders or forks, a coöperating split or double knife comprising two flat blades and shanks of spring material, and a cam for separating the two members or blades of said split or double knife 110 acting on said spring shanks, substantially as specified. 115

4. In a peach splitting and pitting machine, the combination with an intermittently rotatable knife carrier or wheel, fur- 120

125

nished with a series of knives having recessed cutting edges mounted thereon, of a coöperating split or double knife having shanks of spring material, a pair of movable 5 pit holders or forks reciprocating transversely between said knives, a cam for acting on said spring shanks and separating the two members or blades of said split or double knife and thus forcing the split halves 10 of the peach from the pit, and a lever fulcrumed on the frame of the machine to which both of said spring shanks are fixedly attached, substantially as specified.

5. In a peach splitting and pitting machine, the combination with an intermittently rotatable knife carrier or wheel, furnished with a series of knives having recessed cutting edges mounted thereon, of a coöperating split or double knife, and a pair 20 of movable pit holders or forks reciprocating transversely between said knives, means for separating the two members or blades of said split or double knife thus freeing the split halves of the peach from the pit, a lever fulcrumed on the frame of the machine carrying both parts of said double knife, and a pair of strippers, substantially as specified.

6. In a peach splitting and pitting machine, the combination of a knife which is held from lateral movement, and is formed 30 with a notched cutting edge, a double or split knife formed with recessed cutting edges and arranged to overlap or telescope with the first knife one part of the double 35 knife at each side of the same, and means for moving the two parts of the double knife laterally and oppositely away from the first knife, substantially as and for the purposes set forth.

40 7. In a peach splitting and pitting machine, the combination with an intermittently rotatable knife carrier or wheel furnished with a series of knives having recessed cutting edges, of a pair of transversely 45 reciprocating pit holders or forks, a coöperating split or double knife comprising two flat blades having shanks of spring material, a cam acting on said spring shanks for separating the two members or blades of said split or 50 double knife, a lever with which both of said spring shanks are fixedly connected, and a pair of strippers, substantially as specified.

8. In a peach splitting and pitting machine, the combination of a rotary knife carrier furnished with a series of knives having recessed cutting edges, means for holding 55 said knives from lateral movement and for moving them longitudinally and intermittently, two opposing knives formed with recessed cutting edges and arranged to telescope with the knives of the said series on opposite sides of the same, and means for moving said two opposing knives laterally and oppositely away from a knife of said series of knives at the time when the three 60

knives are telescoped and the carrier is intermittently stationary, substantially as and for the purposes described.

9. In a peach splitting and pitting machine, the combination of a rotatable knife 70 carrier, a series of knives having recessed cutting edges and mounted on said carrier, mechanism for turning said carrier intermittently to bring said knives successively opposite to a double knife, said double or split 75 knife having separable blades arranged in the plane of said series of knives and movable in such plane toward and from the knives of said series, mechanism connected with the mechanism for turning the carrier 80 and arranged to separate the blades of the double knife at times when the carrier is intermittently stationary, and the transversely operating pit holders, substantially as and for the purposes set forth.

10. In a peach splitting and pitting machine, the combination of a rotatable knife carrier, a series of knives having recessed cutting edges, and mounted in said carrier, mechanism for turning said carrier intermittently to bring said knives successively opposite to a double knife, said double or split 90 knife having separable or thin blades arranged in the plane of said series of knives and movable in such plane toward and from the knives of said series, a lever with which the parts of said double knife are connected, means for actuating the lever, and mechanism connected with the said mechanism for turning the carrier and arranged to separate 95 the blades of the double knife at times when the carrier is intermittently stationary, substantially as and for the purposes set forth.

11. In a peach splitting and pitting machine, the combination of a rotatable carrier, 105 a series of knives having recessed cutting edges and mounted on said carrier, mechanism for turning said carrier intermittently to bring said knives successively opposite to a double knife, said double or split knife having separable blades arranged in the plane of said series of knives and movable in such plane toward and from the knives of said series, and a cam connected with the mechanism for turning the carrier and arranged to 110 separate the blades of the double knife at times when the carrier is stationary, said cam being arranged and movable in planes parallel with the planes of rotation of the carrier, substantially as and for the purposes 115 set forth.

12. In a peach splitting and pitting machine, the combination of a rotatable knife carrier, a series of knives having recessed cutting edges and mounted on said carrier, 125 mechanism for turning said carrier intermittently to bring said knives successively opposite to a double knife, said double or split knife having separable blades arranged in the plane of said series of knives and movable in 130

said plane toward and from the knives of said series, a pivot to which both of said blades are attached to turn therewith, means for oscillating said blades and pivot, and 5 mechanism connected with the mechanism for turning the carrier and arranged to separate the blades at times when the carrier is intermittently stationary, substantially as and for the purposes set forth.
